UNITED STATES PATENT OFFICE.

AUGUST R. RIEGER, OF CHICAGO, ILLINOIS.

CIGARETTE HOLDER.

Application filed May 25, 1922. Serial No. 563,470.

To all whom it may concern:

Be it known that I, AUGUST R. RIEGER, a citizen of the United States, residing at Chicago, in the county of Cook and State of

5 Illinois, have invented a certain new and useful Improvement in Cigarette Holders, of which the following is a specification.

This invention relates to that type of cigarette holders in which means is provided 10 for ejecting the stub of the cigarette, and the present improvement has for its object:—

To provide a structural formation and association of parts whereby the ejection of 15 the cigarette stub is effectively attained, by a movement of the one hand of the user, and a simple jerking action of the same, all as will hereinafter more fully appear.

In the accompanying drawing:—

20 Fig. 1, is a longitudinal central section of a cigarette holder embodying my invention, with the parts in position for use.

Fig. 2, is a similar view with the parts shown in an ejector position.

25 Fig. 3, is a longitudinal section, with the movable parts shown in elevation.

Like reference numerals indicate like parts in the different views.

Referring to the drawing, 1 designates the 30 main shell of the holder having the usual longitudinal bore, the forward end of which is formed with the usual flaring portion 2 to receive and hold the end of a cigarette. In the preferred construction shown, the main shell 1 is formed in sections 35 adapted to be screwed together, to afford convenient access to the piston chamber hereinafter described for cleaning purposes and the like.

40 In the present improvement the longitudinal bore of the shell 1 is formed intermediate of its length with an enlarged piston chamber or cavity 3 having connection by a reduced guide passage 4 with the aforesaid flaring portion 2 of the longitudinal bore.

45 5 designates a head or piston moving in the piston chamber 3 and preferably formed with a central passage 6 for a free passage of smoke.

50 7 designates a tubular impact member

moving in the reduced guide passage 4, and having stop collars or flanges 8 at its respective ends adapted to prevent its displacement from the holder.

In the operation of the present appliance, 55 a sharp jerk on the part of the hand grasping the holder will cause the piston or head 5 to move and have forcible impact against the impact member 7 to cause the same to move outward and eject the stub of a cigarette from the holder.

Having thus fully described my invention, what I claim as new and desire to secure by Letters Patent, is:—

1. A holder for cigarettes and the like, 65 comprising a main shell formed with a longitudinal bore the forward end of which is enlarged to receive a cigarette end, said bore being enlarged intermediate its length to provide a piston chamber, a piston head 70 having movement in said piston chamber, and means intermediate of said piston head and the forward end of the longitudinal bore for receiving the impact of said piston and transferring the same to the end of a 75 cigarette in said forward end of the holder.

2. A holder for cigarettes and the like, comprising a main shell formed with a longitudinal bore the forward end of which is enlarged to receive a cigarette end, said bore being enlarged intermediate its length to provide a piston chamber, a piston head having movement in said piston chamber, and a tubular impact member guided in the bore of the shell and adapted to receive an 80 impact of the piston and transfer the same to the end of a cigarette in said forward end of the holder.

3. A holder for cigarettes and the like, comprising a main shell formed with a longitudinal bore the forward end of which is enlarged to receive a cigarette end, said bore being enlarged intermediate its length to provide a piston chamber, a piston head having movement in said piston chamber and 85 formed with a central longitudinal bore, and a tubular impact member guided in the bore of the shell and adapted to receive the impact of said piston.

4. A holder for cigarettes and the like, 90

comprising a main shell formed with a longitudinal bore the forward end of which is enlarged to receive a cigarette end, said bore being enlarged intermediate its length to provide a piston chamber, a piston head having movement in said piston chamber, and a tubular impact member having stop flanges

at its respective ends and guided in the bore of the shell, said impact member being adapted to receive the impact of the piston. ¹⁰

Signed at Chicago, Illinois, this 23rd day of May 1922.

AUGUST R. RIEGER.
